US0D1013149S

(12) United States Design Patent (10) Patent No.: US D1,013,149 S
(45) Date of Patent:  Jan. 30, 2024

(54) PORTABLE ELECTRIC FAN FOR OUTDOOR ACTIVITIES

(71) Applicant: Shenzhen Anansheng Electronics Co., Ltd., Shenzhen (CN)

(72) Inventor: Yong Wei, Guangdong (CN)

() Term: 15 Years

(21) Appl. No.: 35/516,897

(22) Filed: Mar. 24, 2023

(80) Hague Agreement Data

Int. Filing Date: Mar. 24, 2023

Int. Reg. No.: DM/228063

Int. Reg. Date: Mar. 24, 2023

Int. Reg. Pub. Date: Apr. 14, 2023

(51) LOC (14) Cl. 23-04

(52) U.S. Cl.

USPC D23/381

(58) Field of Classification Search

USPC D23/370, 378, 380, 382, 411, 314, 328, D23/333
